UNITED STATES PATENT OFFICE.

WILLIAM L. HAVENS AND CHARLES N. SWANSON, OF TOPEKA, KANSAS.

ROOF FOR RAILWAY-CARS.

1,244,087.

Specification of Letters Patent. Patented Oct. 23, 1917.

Application filed January 4, 1916. Serial No. 70,147.

To all whom it may concern:

Be it known that we, WILLIAM L. HAVENS and CHARLES N. SWANSON, citizens of the United States, and residents of Topeka, in the county of Shawnee and State of Kansas, have invented certain new and useful Improvements in Roofs for Railway-Cars, of which the following is a description, reference being had to the accompanying drawings, which form a part of our specification.

Our invention relates to roofs more especially intended for freight cars; and has for its object the provision of a sectional car-roof which may be readily applied or put into place, and at the same time provide a weatherproof construction.

Another object of our invention is to provide a flexible car-roof, the component sections, whereof, when assembled, are capable of unrestricted movement with respect to each other, without, however, impairing the weatherproof qualities of the roof and without causing undue wear on any of the sections and especially at the seams between the respective sections.

A further object of our invention is to provide a car-roof composed of sections yieldingly secured together so as to obviate any possibility of warping, buckling or other distortion of the roof, or any of its sections, through the vibratory wrenching or twisting movements of the car-frame or sheathing.

A further object of our invention is to provide a car-roof composed of sections adapted to be readily secured together and put into place, and which will combine the advantages of minimum cost of manufacture, application and maintenance, while at the same time affording perfect protection for the car contents; the construction being such as to permit the roof to be readily removed and applied to another car or re-applied to the same car without in any way damaging the roof.

Still another object of our invention is to provide a metal roof wherein the necessity for soldered seams will be entirely eliminated and the necessity for using sheet rubber, tar paper, or other materials of like nature, in forming or covering any of the seams or joints will also be obviated.

The above enumerated advantages and others inherent in the construction will be more readily comprehended from the fol-

lowing detailed description of the accompanying drawings, wherein:

Figure 1 illustrates, in perspective, the application of our invention to the roof of a freight car, the upper portion of the car only being shown; portions of the running-board and portions of the roof-sections being shown broken away.

Fig. 2 is a cross sectional view taken on the line 2-2 of Fig. 1, looking in the direction of the arrows.

Fig. 3 is a fragmental sectional detail view taken on the line 3-3 of Fig. 1 looking in the direction of the arrows.

Fig. 4 is a similar view taken on the line 4-4 of Fig. 1 looking in the direction of the arrows.

Fig. 5 is a longitudinal sectional view taken on the line 5-5 of Fig. 2 looking in the direction of the arrows.

Fig. 6 is a detail perspective view of the running-board end flashing.

Fig. 7 is a perspective view of a portion or one end of our improved ridge cap.

Fig. 8 is a similar view of a portion or one end of an eave-flashing.

Fig. 9 is a detail perspective view of a running-board roof-section, portions of the side edges being broken away in order to more clearly illustrate its construction.

Fig. 10 is a detail perspective view of a main roof-section.

Fig. 11 is a detail perspective view of a main roof holding clip.

Fig. 12 is a cross sectional view of the main roof-section, taken on the line 12-12 of Fig. 10 looking in the direction of the arrows.

In the particular exemplification of our invention, as disclosed in the drawings, the main portion of the car roof comprises a suitable number of sections 15 each composed of sheet metal preferably cut in the form of a parallelogram, as more clearly shown in Fig. 10. The sheet after having been cut to the desired length and width has its lower edge turned back upon itself, as indicated in dotted lines at 16 in Fig. 10 and in section in Fig. 2. The bent end 16 is adapted to be on the under side of the roof-section when the same has been put into place, in order to form an interlocking seam with the eave-flashings 17, as shown in Fig. 2.

Before the main roof-section 15 is put

into place, its side edges are first beaded in the manner shown at 18, 18, see Figs. 10 and 12, after which the longitudinal side edges of the section are bent over, as shown at 19 and 20 in Figs. 10 and 12, so as to provide a formation, in cross-section, somewhat in the nature of the letter U. The edge 19 is bent over substantially parallel with the under side of the main roof-section, while the edge 20 is bent over substantially parallel with the upper side of the section, thus permitting the flange or bent edge 19 of one section to interlock with the flange or bent edge 20 of an adjacent section, while the flange or bent edge 20 is adapted to interlock with the flange or bent edge 19 of the main roof section placed adjacent said side of the section, as disclosed in Figs. 3 and 4.

As before stated, the lower bent edge 16 of the main section 15 is adapted to interlock with the eave-flashings 17, which is shown in detail in Fig. 8, while the method of interlocking is disclosed in Fig. 2. These flashings 17, which are arranged along the longitudinal edges or eaves of the car-roof, are formed preferably of long rectangular pieces of sheet metal bent so as to substantially constitute an angle bar, with one of the sides or legs of the angle being bent back upon itself for a short distance, as shown at 21, in Fig. 8, while the other or upper leg is bent back upon itself substantially to the extent of its entire width, as shown at 22 in Fig. 8, so as to provide a formation, in cross-section substantially in the nature of a horizontally disposed U. The side or leg having the bent portion 21 is adapted to lie flush against the eaves of the car-roof or car-framing, as shown in Fig. 2, while the leg or side having the bent portion 22 is adapted to extend parallel with the roof-sheathing and to interlock with or receive the bent lower edge 16 of the main roof-sections 15, and thereby hold the roof-sections in place.

With the main roof-sections formed as herein shown and described, the sections may be assembled by entering the bent edge 19 of one section between the bent edge 20 of an adjacent section at the end of the sections and sliding the sections into proper relation with each other, that is, by telescoping the sections from end to end at their edges, as more clearly disclosed in Fig. 4. The seam thus formed between adjacent sections permits of sliding movement when necessary, in order to allow the roof to conform with the twisting or distorting movements of the car; the relation of the sections to one another, however, being such as to prevent any possibility of leakage at the seams.

The longitudinal center of the roof, after the sheathing has been put into place, is provided with a ridge-pole 23, see Figs. 1

and 2, extending throughout the length of the car-roof. The ridge-pole 23, as well as the running-board anchor-blocks 24, are held or secured in place by a suitable number of anchor-bolts 25, shown in Fig. 2, the bolts 70 preferably extending through the ridge-pole 23, located in the car interior, as shown, and held in place by nuts, as shown in Fig. 2, on the lower exposed ends of the bolts, namely within the car.

The ridge-pole 23 is preferably provided with curved longitudinal sides, as shown, adapted to receive the inner ends of the main roof-sections 15; the ends of the roof-sections being slightly curved, as shown in Fig. 80 10, in order to conform to the sides of the ridge-pole 23.

After the various roof-sections 15 have been put into place, and before the running-board anchor-blocks 24 are put into place 85 the upper surface of the ridge-pole 23 and the inner ends of the roof-sections 15 are covered with a ridge-cap 26, which is formed of a rectangular piece of sheet metal, with the longitudinal edges preferably beaded, as shown at 27, see Fig. 7. The sheet metal strip is then formed into the channel form, more clearly shown in Fig. 7, so as to conform in cross-section somewhat to the general contour of the ridge-pole 23. 95

By providing the longitudinal edge of the ridge-cap with the beaded formation shown in the drawings, Fig. 7, wear between the contacting portions of the metal sheets is thereby reduced to a minimum.

After the ridge-cap 26 has been put into place, the running-board anchor-blocks 24 are bolted into place, thereby securely clamping the ridge-cap 26 down onto the ridge-pole 23.

The running-board anchor-blocks 24 are preferably made of wood and shaped on the under surface so as to conform somewhat to the upper surfaces of the ridge-cap and sloping angle of the main roof; that is, the 110 under surface of the anchor-blocks 24 are provided with a channel of increasing width toward the bottom of the block, as shown in Fig. 2. The ends or sides of the blocks are cut under or notched to receive the longitudinal running-board sills 27, 27.

A suitable number of anchor-blocks 24 are employed and preferably alternated along the sills 27, 27, with the running-board supports 28.

The running-board sills and running-board supports are of the usual construction employed on freight cars and therefore need no further or more specific description.

It is evident from the construction just 125 described, that when the anchor-blocks 24 are secured in place by the anchor-bolts 25, they not only afford a substantial foundation for the running-board, but they also securely clamp the various parts here- 130

tofore described in place and keep the ridge-cap 26 in such close contact with the roof-sections that it is impossible for rain to be driven under the ridge-cap.

6 After the running-board sills 27, the anchor-blocks 24 and the running-board supports 28 have been put into place, the whole is covered with what we have termed running-board roof-sections 29. The running-board roof-sections 29 are preferably formed of rectangular pieces of sheet metal, with their longitudinal sides bent into the box-like formation, more clearly shown in Fig. 9 that is, with the immediate sides or edges 15 off-set so as to come intermediate of the vertical planes occupied by the upper side edges of the sections, and thereby provide the shoulders or off-sets as shown at 30 in Fig. 9. This permits the sides of the running-board 20 roof-sections to extend beneath the ends of the anchor-blocks 24 and running-board supports 28, which are made to slightly overlap the sills 27, as shown in Fig. 2, thus allowing the lower vertically disposed portions or 25 flanges 31 of the running-board roof-sections to extend parallel with and fit up flush against the sides of the sills 27, 27.

The ends of the running-board roof-sections 29 are made to extend somewhat beyond the main portion of the sections, in order to provide an overlapping end 32 and an engaging or interlocking end 33. The end 33 is preferably given the form of a channel, lying below the plane of the upper 35 surface of the roof-section 29, as more clearly shown in Fig. 9, so as to adapt it to extend beneath the running-board supports 28, as shown in Fig. 5. The channel end 33 is made slightly narrower than the width of the running-board roof-sections in order to 40 enable the end 33 to fit between the running-board sills 27, 27.

The opposite end 32 of the running-board roof-section is adapted to overlap the opposite or channel end 33 of the adjacent section a sufficient distance so as to provide a lap joint; and this end of the roof-section, at a point slightly removed from the immediate end, is provided with a channel-like 50 formation or ridge 34, whereby a corresponding depression or channel is formed on the under surface, adapted to fit over the top of the running-board support, as disclosed in Fig. 5. The channel-like formation or ridge 34 is preferably provided with a series of holes 35, in order to permit this end of the running-board roof-sections to be nailed or screwed to the running-board supports 28 without damaging the metal of the 55 roof-section.

The running-board roof-sections 29 are also provided with ridges 36 and 37, arranged at predetermined points, for the purpose of reinforcing and stiffening the 60 roof-sections; the ridge 37 also acting as a

stop for the overlapping end 32 of the adjacent running-board roof-section which forms a lap seam, as disclosed in Fig. 5.

The running-board roof-sections 29 are preferably of such length as to extend from 70 one running-board support 28 to the other, and thus overlap the intervening running-board anchor-blocks 24; and the ridges 36 are formed at a point where the roof-sections overlap the anchor-blocks 24, so that the 75 ridges 36, or rather the indentation on the under surface resulting therefrom, will provide clearance for the heads of the running-board anchor-bolts 25, as shown in Fig. 5.

At the ends of the running-board, we prefer to provide the running-board end flashings 38, shown in detail in Fig. 6, and the location thereof disclosed at the left-hand of Fig. 1. These end flashings 38 are formed of rectangular pieces of metal bent into the 80 right angular formation disclosed preferably so as to provide legs or portions of unequal length. The lower side or portion of the flashings is secured against the end of the car with the short portion or leg extending 85 between the running-board sills 27, 27, so as to enable this portion to be secured under the ends of the running-board and thereby prevent the entrance of rain and the like at 90 this point, and therefore prevent the elements entering at the ends of the ridge-pole and ridge-cap.

In order to more securely hold the main roof-sections 15 in place, and especially while the sections are being laid, we prefer to employ the section-holding clips 39, shown in detail in Fig. 11. The clips 39 are preferably formed of strips of sheet metal having one end bent back upon itself, as shown at 40, while the opposite end 41 is slightly offset so as to permit it to lie flush with the sheathing of the roof, while the main or body portion is adapted to overlap the interlocked edges or seams of the roof-sections, as shown in Figs. 1 and 3; the under-bent end 40 of the clips 39 being adapted to extend about the bent edge 20 of the main roof-section 15, and at the same time permit of the insertion of the bent edge 19 of the adjacent roof-section 15, to form 105 the interlocking seam shown in Fig. 3. The clips 39 are applied as the main roof-sections 15 are laid, being interlocked with the edge of the section last laid, as just described, while the end 41 is nailed to the sheathing 110 and finally covered entirely by the next main roof-section 15. Any suitable number of clips 39 may be employed, and, if desired, a clip employed for each interlocking seam 115 of the roof-sections; the clips being preferably applied at a point intermediate of the ends of the roof-sections, towit substantially at a central point, as shown in Fig. 1.

Our improved car-roof and running-board roof are applied in the following manner. 130

The ridge-pole 23 is first put into place along the longitudinal center line of the car-roof, after which the eave-flashings 17 are applied along the longitudinal sides of the car-roof by nailing or screwing the same to the framing of the car, as shown in Figs. 1 and 2. The main roof-sections 15 may then be laid by preferably first laying the end roof-sections on opposite sides of the ridge-pole; these sections being so applied as to leave a sufficient overhanging portion which may be bent downward over the end of the roof so as to completely cover the sheathing at the ends of the car. After the first sections have been put into place, a holding clip 39 is then applied to hold down the middle portion of the first section, when the next section is put into place by sliding the sections with their interlocked edges, as previously described, namely with the downwardly bent edge 19 of one roof-section overlapping and interlocking with the upwardly bent edge 20 of the first laid section.

When the opposite end of the car-roof has been reached and the last roof-section is found to be too wide, it may be cut down to suit the width or space remaining to be covered; a suitable portion of the section, however, being left to extend beyond the roof so as to permit this extended portion to be bent downwardly over the end of the sheathing, where it is secured in place in any suitable manner.

We prefer in applying the roof-sections to have them set at an angle as shown in Fig. 1, namely so as not to have them run absolutely square with the car or at right angles to the car sides, but rather at an inclination, in order that the slope of the roof will cause the water to flow away from the open side of the seams. In applying the roof in the manner just described, moisture will be prevented from collecting in the enclosed portions of the seams and thus prevent rusting and corrosion in these places.

By providing the various roof-sections and contacting metal portions with beaded or rounded edges, as hereinbefore described, undue wear, which would otherwise result from the contact of sharp edges, is prevented.

After the main roof-sections are all in place, their upper or free ends are made to conform to the side of the ridge-pole 23, after which the ridge-cap 26 is put into place and the framework of the running-board, to wit the longitudinal sills 27, 27, supports 28 and anchor-blocks or saddles 24 put into position and firmly secured by means of the anchor-bolts 25, which extend through the anchor-blocks or saddles 24; the supports 28 being secured to the sills 27, 27. The running-board roof-sections 29 are then applied in the manner previously described by sliding them in place from the end of

the running-board framework. The running-board roof-sections 29 having been placed into position and made to overlap each other, as hereinbefore described, the running-boards 42 are then secured in place by nails or screws preferably placed so as to take through the holes 35 of the running-board roof-sections 29 and into the running-board supports 28. The running-board having thus been completed, the end-flashings 38 are then secured in place by nailing the same to the ends of the car and also to the underside of the running-board framework.

The main roof-sections, at the eave ends thereof, are then preferably provided with the clips 43 made of suitable metal and provided with an angular portion adapted to overlap the roof-sections, and preferably at the seams thereof, while the other portion is arranged to be secured to the car-framing in any suitable manner as, for example, by the bolts 44, see Fig. 2; the upper or roof-engaging portion of the clips being preferably made wider and with a channeled portion adapted to receive the increased thickness caused by the seams of the roof-sections, as shown in Fig. 1. The clips 43 assist the eave-flashings in holding the end of the roof-sections in place.

We have shown and described what we believe to be the simplest and best form of our invention, but it will be understood that the same may be altered in certain details to conform with various car constructions and as practice may dictate, without, however, departing from the spirit of our invention; and we do not wish to be understood, therefore, as limiting ourselves to the exact constructions shown and described.

What we claim is:

1. In combination with a sectional sheet metal car roof, a ridge-pole cap comprising a continuous sheet metal channel, the longitudinal sides whereof are prevented downwardly, with the longitudinal edges bent back upon the under side so as to extend substantially parallel and in intimate relation with the inner ends of the roof-sections.

2. In a railway car roof, running-board roof-sections composed of rectangular sheets of metal having their longitudinal sides bent downwardly so as to lie flush against the sides of the running-board sills, one end of each roof-section being off-set so as to extend into a plane beneath that of the upper surface of the section while the other end of the section is extended so as to overlap the offset end of the adjacent roof-section.

3. A railway car roof comprising a ridge-pole arranged along the longitudinal center line of the roof above the sheathing, roof-sections arranged obliquely to the ridge-pole with their inner ends overlapping the sides of said pole while the opposite ends

105

110

115

120

125

130

- of said sections are bent back parallel with the undersides thereof, the longitudinal sides of each section being bent back parallel with the main portion thereof, one side being bent parallel with the upper surface while the other side is bent parallel with the lower surface so as to permit the side of one section to interlock with the side of an adjacent section, eave-flashing, the one longitudinal edge whereof is bent back upon the upper side and adapted to engage with the bent outer end of the roof-sections, a sheet metal ridge-cap adapted to extend over the ridge-pole and provided with downwardly presented sides, the edges whereof are bent back upon the lower side of the cap so as to engage with the inner ends of the roof-sections, running-board anchor-blocks provided with recesses on the lower sides adapted to receive the ridge-pole and ridge-cap, and means extending through said anchor-blocks, ridge-cap and ridge-pole whereby said parts are secured in place.
25. 4. A railway car roof composed of a series of sheet metal sections, one longitudinal edge of each section being bent back parallel with the lower side thereof while the other longitudinal side of each section is bent back parallel with the upper side thereof, said roof-sections being arranged obliquely to the longitudinal center line of the car-roof so as to cause water to shed toward the longitudinal side of the sheet which is bent back parallel with the under surface of the section, in combination with a continuous ridge-member formed of sheet metal bent into channel form with the sides of the channel disposed downwardly, the longitudinal edges of the ridge-member being bent back upon the underside so as to extend substantially parallel and in engagement with the inner ends of the roof-sections.
45. 5. A railway car roof provided with running-board sills, members extending transversely of the sills to secure the sills in place and to provide supports for the running-boards, roof-sections composed of rectangular sheets having their sides bent downwardly so as to provide longitudinally disposed channels adapted to receive the ends of said members and to provide a flanged portion adapted to lie flush against the sills, one end of each roof-section being offset so as to extend in a plane beneath that of the upper surface of the section and arranged to fit about said members intermediate of the sills, while the other end is extended so as to overlap the offset end of the adjacent roof-section.
55. 6. In a railway car roof, running-board roof-sections composed of rectangular sheets of metal, the longitudinal sides of each sheet being bent downwardly and offset so as to bring the free edges of the sheet into vertical planes within the vertical planes of the upper side edges of the roof-sections, the upper or main portion of the roof-sections being provided with transversely disposed reinforcing ribs or ridges, with one end of the main portion of each roof-section extending beyond the longitudinal side and offset so as to extend in a plane beneath that of the upper surface of the section, said extended end being channeled so as to fit about the running-board support, while the opposite end of the running-board roof-section is extended so as to overlap the offset end of the adjacent running-board roof-section.
7. A railway car roof provided with running-board sills, members extending transversely of the sills to secure the same in place and provide support for the running-boards, running-board roof-sections composed of rectangular sheets having their sides bent downwardly so as to provide longitudinally disposed channels adapted to receive the ends of said members and to provide flanged portions adapted to lie flush against the sides of the sills, one end of each roof-section being offset so as to extend in a plane beneath that of the upper surface of the section and arranged to fit about said members intermediate of the sills, while the other end is extended so as to overlap the offset end of the adjacent roof-section, the main portion of the roof-sections being provided with transversely disposed reinforcing ribs or ridges.
8. A railway car roof provided with running-board sills, members extending transversely of the sills to secure the same in place and provide support for the running-boards, roof-sections composed of rectangular sheets having their sides bent downwardly so as to provide longitudinally disposed channels adapted to receive the ends of said members and to provide flanged portions adapted to lie flush against the sides of the sills, and end-flashing or members adapted to be secured to the ends of the car or framing mid-to the under side of the running-boards.
9. A railway car roof provided with running-board sills, members extending transversely of the sills to secure the same in place and provide support for the running-boards, running-board roof-sections composed of rectangular sheets having their sides bent downwardly so as to provide longitudinally disposed channels adapted to receive the ends of said members and to provide flanged portions adapted to lie flush against the sides of the sills, one end of each roof-section being offset so as to extend in a plane beneath that of the upper surface of the section and formed so as to fit about said member, and intermediate of the sills, while the other end of the section

6
is extended so as to overlap the offset end of the adjacent roof-section, said roof-sections being provided with transversely disposed reinforcing ribs or ridges, and end-flashings or members adapted to be secured to the car-ends or framing and to the under side of the running-boards.

10. A railway car roof provided with running-board sills, members extending transversely of the sills to secure the same in place and to provide support for the running-boards, running-board roof-sections composed of rectangular sheets having their sides bent downwardly so as to provide longitudinally disposed channels adapted to receive the ends of said members and to provide flanged portions adapted to lie flush against the sides of the sills, one end of each roof-section being offset so as to extend in a plane beneath that of the upper surface of the section and formed to fit about said members and intermediate of the sills, while the other end of the section is extended so as to overlap the offset end of the adjacent roof-section, each section at a point in proximity to the last mentioned end, being provided on its under side with a transversely disposed channel adapted to receive the upper surface of one of said members, and means whereby said last mentioned end of each section is secured to said members.

11. In a railway car roof, running-board roof-sections composed of rectangular sheets of metal having their longitudinal sides bent downwardly and offset so as to have the free edges extend in planes intermediate of the vertical planes of the sides of the main portion so as to provide channels

adapted to receive the ends of the running-board supports while the free edges are adapted to lie flush against the sides of the running-board sills.

12. In a railway car roof, a running-board roof composed of sheet metal having the longitudinal sides bent downwardly and offset so as to have the free edges extend in vertical planes intermediate of the vertical planes of the sides of the main portion so as to provide channels adapted to receive the ends of the running-board supports, while the free edges are adapted to lie flush against the sides of the running-board sills, the main portion being provided on its under side with transversely disposed channels at points coincident with the running-board supports.

13. In a railway car roof, a running-board roof composed of sheet metal having the longitudinal sides bent downwardly and offset so as to have the free edges extend in vertical planes intermediate of the vertical planes of the sides of the main portion so as to provide channels adapted to receive the ends of the running-board supports, while the free edges are adapted to lie flush against the sides of the running-board sills, the main portion being provided on its under side with transversely disposed channels at points coincident with the running-board supports and with transversely disposed reinforcing ribs or ridges.
